UNITED STATES PATENT OFFICE.

FRANK LOWELL BUTLER, OF CHICAGO, ILLINOIS.

ELECTRIC FIXTURE.

1,391,612.

Specification of Letters Patent. Patented Sept. 20, 1921.

Application filed November 26, 1920. Serial No. 426,496.

To all whom it may concern:

Be it known that I, FRANK LOWELL BUTLER, a citizen of the United States, and resident of Chicago, in the county of Cook, and 5 State of Illinois, have invented a new and useful Improvement in Electric Fixtures, of which the following is a full, clear, and exact description.

My invention relates to improvements in 10 electric fixtures, and it consists in the combinations, constructions and arrangements herein described and claimed.

An object of my invention is to provide 15 improvement over the electric fixture disclosed in my prior application for patent, Serial No. 423,638, filed November 12, 1920, said improvement consisting in provision in a fixture of the type described of novel means for guiding the electrical conducting members through a lateral aperture in the stem 20 and for maintaining the stem in assembled condition.

A further object of my invention is to 25 provide an improvement over the electric fixture disclosed in my prior application for Letters Patent, Serial No. 423,400, filed Nov. 11, 1920, in which I disclose a tubular insulating member threaded interiorly at its lower end for engagement with a nipple and 30 a casing mounted on the tubular insulating member, having a flange abutting the insulating member and being maintained on the latter by a fitting screwed on the nipple, said improvement consisting in the provision of 35 diametrically opposed grooves in the edges of the inwardly turned flange of the casing and in the provision of a somewhat different means for supporting said nipple.

A further object of my invention is to 40 provide a device of the type described that is relatively simple in construction, thoroughly effective for the purpose intended, and not likely to get out of order easy.

A further object of my invention is to 45 provide a device of the type described in which the number of component elements are reduced to a minimum, thereby permitting the provision of a device that can be manufactured cheaply and is thoroughly practical 50 commercially.

Other objects and advantages will appear in the following specification, and the novel features of the invention will be particularly pointed out in the appended claims.

55 My invention is illustrated in the accom-

panying drawings, forming part of this application in which—

Figure 1 is a central section through the preferred form of the device,

Fig. 2 is a similar view of a fragmentary portion of a modified form of the device,

Figs. 3, 4 and 5 are similar views, partly in elevation and partly in section of fragmentary portions of modified forms of the device.

Figs. 6 and 7 are similar sectional views of fragmentary portions of still other modified forms of the same device,

Fig. 8 is a section along the line 8—8 of Fig. 6, and

Figs. 9, 10, 11, 12, and 13 are vertical sectional views of fragmentary portions of stems in other modified forms of the device.

Referring now to Fig. 1, it will be noted that I make use of a fixed support such as 75 a gas pipe 1 that depends from a ceiling 2. A tubular insulating member 3 is threaded exteriorly at 4 adjacent its upper end for engagement with a coupling 5 that is fitted on the threaded end of the gas pipe 1. The 80 coupling 5 is formed with the usual transverse partition 6 therein intermediate its length.

A tubular metallic member 7 is projected over the lower portion of the insulating 85 member 3 and is formed with an inwardly extending flange 8 at its upper end, arranged to enter an annular groove 9 in the outer wall of the insulating member. The annular groove 9 is positioned at a spaced distance from the lower end of the insulating member 3, wherefore a sufficient length of the tubular insulating member 3 is disposed between the lower end of the coupling 5 and the upper end of the metallic tubular member 7 to thoroughly insulate the latter member from the coupling and to preclude the possibility of an electric current passing across the gap. A diametrically disposed pin 10 extending through the walls of the 100 insulating member 3 and the tubular metallic member 7 aids in maintaining the flanged end 8 in the groove 9 against a stress placed on the tubular metallic member by the weight of an electric lighting fixture, not 105 shown, that will be supported thereby.

The tubular metallic member 7 is formed with an inwardly extending flange 11 at its lower end adapted to support a nut 12 that is inserted within the tubular metallic mem-

ber 7 at the upper end thereof and is moved into the position shown. An eye member 13 is formed with an exteriorly threaded tubular extension 14 fitting the threaded bore of the nut 12, the movement thereof being limited by a shoulder 15 that abuts against the flange 11 when the eye member 13 is in adjusted position as shown. Electrical conducting wires 16 are passed into the tubular metallic member 7 through the bore 17 of the extension 14 to the eye member 13 and are guided therefrom through a lateral aperture 18 in the tubular metallic member 7 by inclined coöperating lugs or tongues 19 and 20 that are integral with the tubular metallic member 7. The guiding member so described is provided by making slits or kerfs through the walls of the tubular metallic member 7 at diametrically opposed points and at spaced distances from the upper end of the latter. The portions of the walls outlined by such kerfs are bent inwardly until the adjacent surfaces thereof contact, as shown.

25 A canopy 21 is mounted on the tubular metallic member 7 and secured in adjusted position therealong by means of a set screw 22.

From the foregoing description of the various parts of the device, the operation thereof may be readily understood. The several parts described can be assembled quickly and readily to provide a fixture that is at once effective for the purpose intended, 35 simple in construction, strong and durable, and ornamental in appearance. Heretofore difficulty has been experienced in guiding the electrical conducting wires from the stem 7 into position to engage with the electrical conducting means, not shown, that are ordinarily installed to depend from the ceiling 2. It will be seen that the guiding lugs or tongues 19 and 20 will divert the wires 16 through the opening 18 and that the delay 45 in installing a fixture occasioned heretofore on account of the time consumed in "fishing" for the wires 16 will be obviated.

In Fig. 2 I show a modified form of the same device in which a tubular metal member 30 is substituted for the insulating member 3. The tubular member 30 is provided with an annular groove 31 adapted to receive the flange 8 of the tubular stem member 7. A pin 32 extending through the walls 50 of the tubular metal member 30 and of the stem member 7 insures the maintenance of the members 7 and 30 in adjusted position relative each other. The tubular metal member 30 is threaded exteriorly at 33 adjacent its upper end and is therefore adapted for operative engagement with the coupling 5 or with an ordinary insulating joint, not shown, if the requirements of the service to which the device is applied are such as to necessitate the provision of an insulated stem.

A guiding tongue 34 is provided by slitting the side wall of the member 7 adjacent the upper end thereof and by bending the portion outlined by the slit inwardly until the end thereof contacts with the inner wall 70 of the metallic member 7. The electrical conducting member 16 will be guided through the aperture 35 that is provided by the displacement of the tongue 34.

Referring now to Figs. 3, 4, and 5 it will 75 be observed that I may adapt the device to provide electric brackets. In the device shown in Fig. 3 a bracket member 40 has an exteriorly threaded tubular extension 41 arranged to engage the threaded bore of the 80 nut 12. It will be understood that the bracket member 40 is adapted for operative connection with a socket or the like, not shown, that supports an ordinary electric lighting fixture. The electrical conducting 85 wires 16 pass into the tubular metallic member 7 through the bore 42 of the extension 41.

In the form of the device shown in Fig. 4, a close nipple 50 engages the threaded bore 90 of the nut 12. A suitable bracket member 51 is formed with an interiorly threaded portion 52 for engagement with the end of the nipple 50. The electrical conducting wires are passed into the tubular metallic member 7 through the nipple 50. 95

In the form of the device shown in Fig. 5, an elbow 60 is fitted on the projecting end of the nipple 50. The electrical conducting wires 16 are passed into the tubular member 7 through the elbow 60 as shown. 100

In the form of the device shown in Fig. 6, the tubular metallic member 7 is formed with an inwardly extending flange 65 at its lower end. The flange 65 is turned upwardly at 66 and supports a washer 67. The upturned portion 66 of the flange 65 is formed with diametrically opposed grooves 68, adapted to engage the remote walls of a link 69 that has spring qualities and is arranged in the position shown by insertion into the 110 stem at the upper end thereof. The link 69 is formed with a shoulder 70 adapted to rest upon a washer 67 and to be supported thereby. The engagement of the side members of the link 69 with the walls of the 115 groove 68 prevents rotatable movement of the former.

In Fig. 7, I show a portion of a form of the device adapted for use with a drop cord 75. A washer 76 that is formed of mica or 120 the like is supported by the flange 11 of the tubular metallic member 7 and projects inwardly beyond the inner edge of the flange. A spring member 77 surmounting the washer 76 maintains the latter in the position shown 125 when the drop cord 75 is passed upwardly into the tubular member 7 through the central opening 78 in the washer 76.

In Figs. 9 and 10, I show a tubular member 80 reduced at 81 adjacent its upper end. 130

The tubular member 80 is formed with tongues 82 and 83 that are integral therewith and provide a guiding member similar to that formed by the tongues 19 and 20 as hereinbefore described. The reduced upper portion of the tubular member 80 is threaded interiorly at 84 or exteriorly at 85 for engagement with suitable fittings such as coupling 5 or a stud (not shown) that ordinarily depends from the ceiling 2.

Referring now to Figs. 11 and 12, I show a tubular metallic member 90 provided with a tongue 91 to form a guiding member that is precisely identical with that formed by the tongue 34 (see Fig. 2) and therefore requires no further description. An interiorly threaded socket member 92 adapted for engagement with the gas pipe 1 or a similar fitting is inserted within the tubular member 90 at the upper end thereof and is then welded thereto or secured in place in any other suitable manner. In the form of the device illustrated in Fig. 12 an interiorly threaded tubular insert 93 is secured in place within the tubular member 90 in the same manner.

In the form of the device shown in Fig. 13 a coupling 95 has an upper socket 96 threaded interiorly for engagement with the gas pipe 1 or a similar fitting and a lower socket 97 adapted to receive the insulating member 3'. The wall of the lower socket 97 is turned inwardly at its lower end to provide a flange 98 adapted to enter an annular groove 99 in the insulating member 3' when the latter is sprung into the position shown. A pin 100 passes through the walls of the socket 97 and the insulating member 3' to complete the assembly.

I claim:

1. In the electric fixture, the combination of a tubular metallic member having an inwardly extending flange at one end thereof, said tubular member having an opening through its side wall at a spaced distance from one end thereof, said opening being provided by making a slit in the side wall and by bending the portion of the wall defined by the slit diagonally across the bore of the tubular member into position to guide a flexible member contacting therewith through the opening, means for connecting

the tubular metallic member with a fixed support, means engaging with said tubular metallic member for connecting the latter with an electric lighting fixture element to be supported thereby, and flexible electrical conducting means adapted for operative connection with the electric lighting fixture element, said flexible conducting means being passed into said tubular member at one end thereof and guided therefrom through said aperture by said guiding member.

2. In an electric fixture, the combination of a fixed support, a tubular insulating member having an annular groove in its outer wall at a spaced distance from the remote end thereof, means for securing the insulating member to the fixed support, a tubular member arranged to incase the remote portion of said insulating member and formed with an inwardly extending flange arranged to enter said annular groove, said second named tubular member having a diagonally extending guide across its bore at a spaced distance from the insulating member, said guide being formed by making kerfs through the side walls of said tubular metallic member at diametrically opposed points and bending the portions outlined by said kerfs inwardly into contact with each other, thereby providing opposite lateral apertures, said tubular metallic member being formed with an inwardly extending flange at the remote end thereof, means carried by the flange and partially disposed within the second named tubular member for connecting with an electric lighting fixture element, and flexible electrical conducting means passed into said second named tubular member and being guided therefrom through one of said lateral apertures by said guide.

3. In an electric fixture, a stem comprising a tubular member having a portion of its side wall displaced inwardly at a spaced distance from one end thereof to provide a lateral aperture in said wall and a relatively arranged guide member adapted to guide a flexible member from its bore through the lateral aperture, and means for connecting the tubular member to a fixed support.

FRANK LOWELL BUTLER.
